CLAIM

The ornamental design for a multi in one data cable as shown and described.

DESCRIPTION

FIG. 1 is a perspective view of a multi in one data cable, showing my new design;

FIG. 2 is another front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is perspective view thereof, shown in an in-use condition.

The broken lines in the drawings depict portions of the multi in one data cable that form no part of the claimed design.
